POT HOLDER RACK OR SIMILAR ARTICLE

Thomas C. Dinu, Ann Arbor, Mich.

Application May 31, 1952, Serial No. 19,978

Term of patent 7 years

(Cl. D33—16)

To all whom it may concern:

Be it known that I, Thomas C. Dinu, a citizen of the United States, residing at Ann Arbor, in the county of Washtenaw and State of Michigan, have invented a new, original, and ornamental Design for a Pot Holder Rack or Similar Article, of which the following is a specification, reference being had to the accompanying drawing, forming a part thereof.

Fig. 1 is a top plan view of a pot holder rack or similar article, showing my new design;

Fig. 2 is a front elevational view thereof; and

Fig. 3 is an enlarged fragmentary end elevational view thereof, showing the outwardly extending hooks.

I claim:

The ornamental design for a pot holder rack or similar article, substantially as shown.

THOMAS C. DINU.
